UNITED STATES PATENT OFFICE.

GARNET W. COEN, OF SAN FRANCISCO, CALIFORNIA.

OIL HEATER.

Application filed April 13, 1921, Serial No. 461,078.

all whom it may concern.

Be it known that I, GARNET W. COEN, a citizen of the United States, residing at the city and county of San Francisco and State of California, have invented new and useful Improvements in Oil Heaters, of which the following is a specification.

This invention relates to liquid heaters, and especially to a simplified form of the structure shown in my copending application entitled "Oil heater", filed March 30, 1921, Serial No. 457,008.

One of the objects of the present invention is to generally improve and simplify the construction of oil heaters, and especially to provide a structure which will permit a maximum heat transfer to be obtained between the heating medium and the oil or liquid to be heated; thermal efficiency being obtained in this instance, first, by maintaining the oil in a ribbon or film-like condition during its entire passage through the heater; secondly, by maintaining the oil in the state of agitation and under comparatively high velocity; and third, by maintaining the steam or other heating medium employed at high velocity, and by maintaining the main volume of the steam in contact with the surfaces to be heated.

Another object of the invention is to construct a heater which may be readily taken apart for inspection, repairs, etc., but particularly for the purpose of cleaning the same, and which when taken apart will pre-

sent an exposed surface readily accessible for cleaning, scraping or otherwise.

Another object of the invention is to provide a heater which is simple, compact and substantial in construction, comparatively cheap to manufacture, and in which all parts are free to expand without danger of imposing unnecessary strains on the connected parts; further to connect the several pipes leading to and away from the heater in such a manner that stuffing boxes or similar connections may be entirely eliminated.

Further objects will hereinafter appear.

The invention consists of the parts and the construction, combination and arrangement of parts as hereinafter more fully described and claimed, having reference to the accompanying drawings, in which—

Fig. 1 is a side elevation of the heater partially in section.

Fig. 2 is a plan view of the same.

Fig. 3 is a cross-section on line 3—3, Fig. 1.

Fig. 4 is a central vertical section of the heater showing a slight modification thereof.

Crude oils such as employed today for fuel purposes, and particularly crude oils derived from an asphalt base, are becoming thicker and more viscous as time passes due to the heavy extraction of gasoline, kerosene and other products. Crude oils of this character when obtained from the refiners are often so thick and viscous that the oil must be heated to a temperature from 200 to 300° F., and sometimes even more, before it is rendered sufficiently liquid to be readily handled and efficiently atomized by the burners. The heating of fuel oil is therefore not only a necessity, due to the reasons specified, but it also represents more or less of a problem in actual practice as the heaters rapidly lose their efficiency due to the formation of deposits of carbon, asphalt, sand, etc., which rapidly accumulate and adhere to the heating surfaces. Such deposits are, practically speaking, non-conductors of heat and they form a coating which bakes and hardens on the heating surfaces, and furthermore gradually clogs the passages through which the oil is forced. It can, therefore, be readily seen that unless such accumulations are removed from time to time that the heater will become so inefficient as to be practically useless.

Having these problems and conditions to encounter in actual practice, I have developed a heater which is particularly adapted to handle crude oils such as referred to, and which will efficiently heat a given volume of oil if cleaned from time to time. One of the main features of the present invention is, therefore, the provision of a heater which permits a maximum heat transfer at all times, and which can be readily and quickly taken apart for cleaning whenever necessary; further a heater in which the steam or heating medium employed may be utilized to obtain the greatest thermal efficiency possible. I have accordingly constructed a heater consisting of a series of interspaced cylindrical casings mounted one within the other as indicated at 2 and 3. These casings are interspaced as shown to form a liquid flow passage 4 and a centrally disposed heating chamber 5. The outer shell or casing 2 is

closed at its upper end by means of a head member 6, welded or otherwise secured thereto as at 7. The lower end of this casing is provided with an annular flange 8, 5 which is also secured by welding as indicated at 9 and 10. The flange is otherwise drilled to permit insertion of bolts 11, the function of which will hereinafter be described. The inner shell or casing 3 is similarly provided with a head member 12, 10 preferably welded as at 13. The lower end of the casing is supported by a head member 14 and is welded thereto as at 15. The inner casing is furthermore provided with 15 a false bottom section 16, also welded thereto as at 17; said bottom section being inter-spaced with relation to the main head 14, as indicated at 18. The main head 14 is drilled so that the holes will align with the 20 bolt holes formed in the flange 8, and the main head is therefore secured to the flange 8 by means of the bolts 11 shown.

Surrounding the inner shell 3 is a spiral shaped spacing member 19. This member 25 is welded or otherwise secured to the inner shell, and it serves two functions, first that of maintaining the spacing between the shells and maintaining them concentric with relation to each other, and secondly, that of 30 forming a spiral shaped passage through which the oil or liquid to be heated must pass during its flow through the heater. The inlet for oil is formed at the point indicated at 20. This inlet may be connected 35 with a pipe not shown, with a pump which will force the oil through the heater with comparatively high velocity. The oil, in other words, enters the lower end of the spiral shaped passage and discharges from 40 the upper end of said passage to a chamber 21 formed between the head members 6 and 12, and is finally discharged through a pipe 22, welded or otherwise secured in the upper head member 6.

The lower or main head member 14 is provided with two openings through which passes a steam inlet pipe 23, and an outlet pipe 24. The inlet pipe is connected with a boiler or other suitable source of supply, 50 while the discharge pipe 24, through which the condensate discharges, is connected with a trap or other means not here shown. Both pipes are welded to the inner head member 16 and thereby the necessity of 55 employing stuffing boxes or the like to prevent leakage is eliminated. The upper end of the pipe 23 terminates in a goose-neck 25 and it is held in central position within the chamber 5 by means of a spider 26. See 60 Figs. 1 and 3. This spider also serves as a support for a cone-shaped spreader 27, against which the steam impinges when admitted. This spreader deflects the steam which enters at a high velocity against the 65 inner wall of the shell 3 and thereby causes

the main volume of steam to travel down the inner surface of the shell in intimate contact therewith and at high velocity; this being an important feature as it constantly 70 wipes off or removes any condensate which forms and which might collect, thereby maintaining the surface in a condition where maximum heat transfer can take place. It furthermore deflects the main volume of steam to the point or area where actual heat 75 transfer takes place, thus further increasing the thermal efficiency of the heater in general.

In Fig. 4, I have introduced an inner shell, such as indicated at 28. This shell 80 terminates in a cone-shaped cover section 29 disposed directly below the discharge end of the inlet or goose-neck 25. This shell may be constructed of comparatively thin sheet iron as it is perforated, as at 30, to prevent 85 formation of a pressure chamber exterior thereof. The shell is of smaller diameter than the interior shell 3 and as such forms 90 an annular passage 31 through which the main volume of steam flows before it condenses and reaches the discharge pipe 24; concentric positioning of the shell 28 being obtained, by forming a plurality of spacing lugs on the exterior thereof as indicated 95 at 32.

In actual practice I find that the greatest heat transfer is obtained when the incoming steam is maintained at high velocity, and when intimate contact is maintained 100 between the steam and the heating or transferring surface. This is efficiently accomplished by the structure shown in Fig. 1, but is even more efficiently accomplished by inserting shell 28, shown in Fig. 4, that is the shell there shown not only forces 105 the steam discharging from the goose-neck 25 outwardly against the inner surface of the shell 3; but it also maintains the main volume of steam in intimate contact therewith, thus doing away to a large extent 110 with the dead space formed in the center of the chamber 5. This dead space is also formed in the shell 28, but no circulation of steam is maintained within this chamber, due to the fact that the perforations 30 115 permit a sufficient amount of steam to enter to balance the pressures.

The present heater is in reality a simplified form of the structure shown in my co-pending application referred to. The present heater is known as a one-way heater as 120 the oil only passes through a single passage before it is discharged.

From the foregoing it will be obvious 125 that the oil to be heated is delivered to the inlet 20 of the heater through a pipe or other suitable means not here shown, which is connected with a pump or similar device. This pump maintains a certain pressure on the oil and this pressure is preferably such that 130

the oil will travel through the heater at a comparatively high velocity. The oil entering will travel upwardly through the spiral shaped passage formed between the inner 5 and outer shells and will then discharge into the upper chamber 21, from which it finally 70 discharges through a pipe 22. The oil during its entire passage through the heater will be maintained in a ribbon or film-like condition. Its velocity throughout will, practically speaking, be maintained constant and as the velocity is fairly high and the path or 75 passage tortuous, it is obvious that sufficient agitation will be obtained to thoroughly mix and uniformly expose the entire oil 15 body to the heating surface presented. The heating surface presented by the inner shell 3 is maintained at maximum efficiency, first, by the high velocity of the steam impinging 20 and travelling downwardly against its inner surface, and, secondly, by the wiping action 25 of said steam.

The heater constructed as illustrated in the present instance is very compact and 30 substantial. The several casings employed are preferably cylindrical and as such may be easily fitted and nested one within the other. The inner casing or shell 3 is entirely supported by the main head member 35 14 and as such is free to expand upwardly without imposing any strain on the exterior shell. The shell 2 is also supported by the main head member and it also is free to expand in every direction without imposing any strain on the inner shell. The joint 40 formed between the flange 8 and the main head 14 is preferably maintained by a gasket as shown, and is in fact the only packed joint required in the whole heater.

To further increase the thermal efficiency 45 of the heater, and more particularly to prevent conduction and radiating heat losses, an exterior jacket 30^a is employed. This jacket is supported by the flange 8 at the lower end and by a ring shaped flange 31^a 50 at the upper end, which is merely slipped over the shell 2; the space formed between the jacket 30^a and the shell 2 being filled with a non-conducting packing, such as asbestos or the like.

In actual practice, if it is desired to clean 55 the heating or exterior surface of the shell 3, it is only necessary to remove the bolts 11 and to break the unions on the pipes 23 and 24. The main head 14 supporting the inner shell 3 and the inlet and outlet pipes 23 and 60 24 may then be extracted. When so extracted it is obvious that the entire exterior surface of the shell 3 is so exposed that it may be quickly and readily cleaned to remove any adhering deposits, whether they be hardened, baked or viscous in nature; furthermore the entire inner surface of the shell 2 is also exposed so this can be quickly 65 cleaned if necessary. Actual practice shows

however that no accumulation forms on this surface as it is not exposed to the direct heat of the steam. With the surfaces cleaned, it is only necessary to re-insert the shell 3, being careful however that a gasket is interposed between the flange 8 and the head 14 before the bolts 11 are placed and tightened. The unions on the pipes 23 and 24 are then connected and the heater is again ready for 75 use.

The provision of the inner bottom or head section 16 is an important feature; first, because it balances the pressure of the steam between the head and bottom sections 12 and 16, thereby relieving the head 14 of this 80 pressure, and secondly, because it permits welding of the pipes 23 and 24, thereby eliminating the use of stuffing boxes, etc. The use of the inner bottom section 16 is of further importance as it materially strengthens 85 the lower head and particularly the annular flange formed thereon. This is an advantage as it permits the head to form a continuous beam between the opposing bolts 11, thereby reducing the bending strains. 90

While certain features of the present invention are more or less specifically illustrated, I wish it understood that various changes in form and proportion may be resorted to within the scope of the appended 95 claims, similarly that the materials and finish of the several parts employed may be such as the experience and judgment of the manufacturer may dictate or varying uses 100 may demand.

Having thus described my invention, what I claim and desire to secure by Letters Patent is—

1. In a heater of the class described, a head member provided with a marginal flange and also having a steam inlet passage and condensate outlet therethrough, a shell permanently connected to said head member, a second shell having an outwardly directed flange at its lower end to rest upon the marginal flange of the head member, said shells being spaced to provide a narrow oil passage between them, an enclosing shell permanently connected to the periphery of the flange of the second shell, closures for the upper ends of the first and second shells, the second shell having an outlet, the enclosing shell having an inwardly directed annular flange at its upper end embracing the upper end of the second shell, and means for detachably securing the flange of the second shell to the flange of the head member whereby the second shell and the enclosing shell and flange at the upper end of the latter may be removed as a unit from co-operative relation with the first shell to expose the co-operative surfaces of the oil passage for cleaning purposes. 110 115 120

2. In a heater of the class described, a head member provided with a marginal 125

flange and also having a steam inlet passage and a condensate outlet therethrough, a shell permanently connected to said head member, a second shell having an outwardly 5 directd flange at its lower end whereby to support the second shell on the marginal flange of the head member, the said shells being spaced apart, a spiral shaped member in the space between the shells to provide 10 a spiral shaped oil passage, an enclosing shell permanently connected to the periphery of the flange of the second shell and spaced from the latter, the enclosing

shell having an inwardly directed annular flange at its upper end which embraces the 15 upper end of the second shell, and means for detachably securing the flange of the second shell to the flange of said head member whereby the second shell and the enclosing shell and the flange at the upper end 20 of the latter may be removed as a unit from co-operative relation with the first shell to expose co-operative surfaces of the oil passage for cleaning purposes.

GARNET W. COEN.
